UNITED STATES PATENT OFFICE

JOHN T. RIDDELL, OF EVANSTON, ILLINOIS

CLEAT STUD HOLDER

Original application filed December 29, 1926, Serial No. 157,670. Divided and this application filed September 7, 1928. Serial No. 304,457.

This invention relates to improvements in apparatus for use in effecting the anchorage of friction cleats to shoes of the type commonly employed by athletes.

5 An object of the invention is the provision of a device for retaining a stud or anchorage member of a shoe cleat in position and in alignment with a device for forming an aperture in the sole of a shoe while such aperture is being formed, and for the introduction of the stud through such an aperture previously made.

A further object is the construction of such a stud or bolt holding or retaining device 15 adapted to easily and quickly receive the bolt and to effectually retain the bolt until introduced through the aperture in the shoe sole.

With these and further objects in view, as will in part hereinafter become apparent, 20 and in part be stated, the invention comprises a temporary retainer for a bolt or like fastener for shoe cleats adapted to effectively support such fastener, and frictionally resist lateral displacement thereof, while being applied to a shoe, and yet readily release the fastener after such application.

Other objects will appear hereinafter.

The subject matter of this application constitutes a division of applicant's co-pending 30 application, Serial No. 157,670, filed December 29, 1926.

The invention consists in the combinations and arrangements of parts hereinafter described and claimed.

35 The invention will be best understood by reference to the accompanying drawings forming a part of this specification, and in which:

Fig. 1 is a view in side elevation of an apparatus incorporating an illustrative embodiment of the invention, parts being broken away and shown in section for disclosing the otherwise concealed structure;

Fig. 2 is a top plan view of the device shown in Fig. 1, the standard and parts beneath being broken away;

Fig. 3 is a front elevation of the parts seen in Fig. 2; and

Fig. 4 is a perspective view of the parts

seen in Figs. 2 and 3, a cleat stud being shown in place.

Referring to the drawings by numerals, 1 indicates a base plate adapted to be anchored by bolts or other attaching means 2 to a bench or other supporting table 3. The table 3 may be the bed plate of a drill press where the super-structure hereinafter to be described is being utilized in connection with the operations of a drill. A standard 4 is 35 socketed or otherwise appropriately anchored in the base 1, and upstands therefrom and is bent to form a horn 5, proportioned to be adapted for ready introduction into and removal from a shoe, the shoe being ordinarily the moved element. The horn 5 upstands from the standard 4 substantially horizontally, and is provided with an upper flat face 6, against which the inner face of a shoe sole is adapted to rest. 50

The free end of the horn 5 is formed into or provided with a vise-like supporting holder for the bolt or stud to be inserted through the sole of an athletic shoe as the anchorage means for a cleat thereof. The receiving 55 vise is susceptible of a wide range of modification, but in one of its simplest forms, as seen in Figures 1 to 3, comprises a pair of jaws 7, having a notch or opening 8 therebetween through which the body 9 of a cleat 60 engaging stud or bolt is adapted to extend. A flat table 10 extends across and is spaced beneath the jaws 7 and notch 8 to receive and support the head 11 of bolt 9. The table 10 65 may be formed, as may all the other parts of the holder, by any advantageous method of construction, one of which consists in forming the free terminus of horn 5 with particular recess 12, into which a disc is inserted with a driving fit to form the table 70 10. Material of the horn 5 immediately above the table is chamfered or otherwise beveled to form a recess 13, having an inclined upper wall for accommodating the incline face of head 11 presented in the direction of the body 9. Obviously the recess 13 may be given any desired contour and configuration 75 adapted to conform with that of the material of the head of the particular type of stud or bolt to be received. It is essential only that 80

the recess be proportioned to receive the head 11 and be open laterally for free introduction and removal of said head. A degree of snugness of fit is desirable to offer sufficient frictional resistance to displacement of the bolt 9 to insure against accidental dislocation thereof. Extending rearwardly from the base of notch 8 between jaws 7, the material of horn 5 is formed with a narrow, slot-like notch 14, reduced in width almost to a slit, but of sufficient area to receive one of the webs or fillets 15 of the stud 9. It will be understood that the said webs or fillets are usually formed as an incident to the method of construction of the stud or bolt 9 during the swaging up of the head thereof, and the exposed edge of each fillet 15 is usually curved. The notch 14, as clearly seen in Fig. 1, is therefore, similarly curved, so that when a bolt 9 is inserted into position, as seen in Fig. 4, with its head resting on table 10 and its body outstanding or upstanding through the slot 8, one of the webs or fillets 15 will lie in the notch 14 and materially add to the resistance to any displacing stresses, particularly torsional, to which the bolt 9 may be subjected while sustained by the supporting holder.

The holder is adapted for the retention of bolts during the various manipulations of parts relative thereto, as, for example, while the sole of a shoe is being forced down over the projecting body 9, and while a clamping nut is being threaded onto the free end portion of said body 9. The supporting holder is also well adapted for sustaining such a bolt as stud 9 while a shoe is located over the horn 5 and the sole of the shoe is being stressed downward upon the projecting body 9, while a drill, such as that of a drill press, is being driven through the sole from above in alignment with the body 9. The flattened upper face 6 enables the inner flat face of the sole of a shoe to contact directly and snugly with the horn as the bolt 9 passes up through the sole, and thus insures projection of the bolt 9 effectively beyond the sole.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

What I claim as new and desire to secure by Letters Patent is:

60 1. A stud support, comprising a horn having a recess adapted to receive the head of a stud, a notch opening laterally from the recess and adapted to accommodate the body of such stud, and a notch of reduced dimensions opening into the first mentioned notch

and adapted to accommodate a fillet extending from the head and the body of said stud, and a table adapted to be engaged by the surface of the head of the bolt opposite said body.

65 2. A holder for studs adapted to be inserted through the soles of athletic shoes, comprising a horn having a pair of jaws between which is formed a notch for the reception of the body of a stud, and a stud head 70 engaging surface beneath said jaws, said horn provided with a recess having inclined side walls between said surface and said jaws for accommodating the head of a stud.

75 In testimony whereof I have signed my 80 name to this specification.

JOHN T. RIDDELL.
